Patented June 22, 1915.

UNITED STATES PATENT OFFICE.

WILLIAM W. ESSICK, OF READING, PENNSYLVANIA.

MOLD FOR LENS-MOUNTING BLOCKS.

1,143,895.

Specification of Letters Patent. Patented June 22, 1915.

Application filed January 19, 1914. Serial No. 812,925.

To all whom it may concern:

Be it known that I, WILLIAM W. ESSICK, a citizen of the United States, residing at Reading, in the county of Berks and State of Pennsylvania, have invented certain new and useful Improvements in Molds for Lens-Mounting Blocks, of which the following is a specification.

My invention relates particularly to lens 10 grinding, and my object broadly is to provide for producing with great economy of labor and a minimum of special skill and judgment, lenses which will conform with extreme accuracy and uniformity to determined requirements.

In the method of grinding commonly employed, a series of the roughly shaped blanks are mounted upon the surface of a holder or "block," and are subjected to abrasive action by a corresponding grinder; the holding surface of the block being commonly of a pitch composition to which the lenses adhere as placed by the operator. In order to insure some degree of accuracy in thus mounting the blanks, facets have been formed on the holding surface to facilitate the proper placing of them; these facets being formed by correspondingly shaped molds for the surfacing pitch composition. 20 The accuracy of the mounting then depends primarily upon the correctness and uniformity of the facet-forming recesses in the mold, and also upon the accurate placing of the lenses upon the facets. It will be readily understood that a very slight variation in the facet-forming recesses, such for instance as is apt to occur through wear of a cutting tool; or a very slight misplacing of the lens or blank relative to the focal 30 axis; will result in a more or less seriously defective lens.

My invention provides for avoiding these defects by insuring the accuracy of the lens-mounting facets upon the holder and the accurate placing of the blanks.

Figure 1 illustrates a lens holder or "block" in cross-section, with the pitch surfacing thereon; the facets to the right of the latter being represented as adapted for mounting the flat blanks for the first grinding, and those to the left for remounting to grind the other surface. Fig. 2 indicates a grinder employed therewith. Fig. 3 is a plan view of my improved lens-block mold, a portion only of the facet-forming segments being shown in position. Fig. 4 is a

cross-section thereof on the line 4—4. Figs. 5 and 6 show one of the facet-forming segments; Fig. 7 is a plan view of the mold therefor with the coping portion removed; 60 Fig. 8 is a cross-sectional view of the complete segment mold; and Fig. 9 shows separately the facet-forming portion thereof, modified in shape as required for producing a second-grind lens holder for convex 65 spherical grinding. Figs. 10, 11, and 12 indicate modified forms adapted for cylindrical grinding.

The holder or block 2 shown in Fig. 1, is of convex form adapted for convexly grinding lenses; a similar concaved form being employed for concave grinding as is well understood. The pitch-surfacing 3 of the holder 2 is shaped on the completed correspondingly concaved mold illustrated in 75 Figs. 3 and 4, the novel construction of which is specifically described.

This improved mold as shown in Figs. 3 and 4, comprises a rigid shell or backing 10, the spherically concaved surface 11 of which 80 is accurately finished to a curvature of greater radius than that of the holder 2—3, as determined by the thickness of the facet-forming segmental lining with which it is provided. This lining is made up of segments 15, 15^a, 15^b, preferably arranged in circular series forming successive zones as indicated; the segments in each zone being exactly alike, but varying in outline from those which form the other zones. These 90 zones are bounded by circles of increasing diameter, *a b c d* as shown, to which the parallel ends 15^c, 15^d of each segment conform, while its sides 15^e, 15^e converge toward the center 16 of the mold, as indicated 95 in Figs. 3 and 5. Each of these segments is provided with a facet-forming recess 17 as shown; and practically absolute accuracy of arrangement of these relative to the focal center, which is an essential requirement, is 100 secured by the use of segment forming molds such as is illustrated in Figs. 7, 8, and 9: the showing being specifically adapted for producing a series of the segments 15^a illustrated in Figs. 5 and 6.

This facet-forming segment mold comprises a base portion 20, a coping portion 21, and an interposed segment-wall portion 22; which portions are formed as illustrated, with parallel spherically curved opposing surfaces, 21^a of which conforms accurately with the surface 11 of the mold shell

10 so as to properly seat upon the latter. The base portion 20, as shown, is formed with a counterbored central opening extending through the boss 25; to which is adjustably fitted a separate facet-forming mold portion 26, having a head 27 fitted to said counterbore, and an oval facet 28 on said head.

As shown in Fig. 8 this projecting oval 10 facet 28 has a flat face; while in Fig. 9 it is shown with a spherically concaved face; one or the other of these being used according as the lens holder to be produced is intended for mounting unground blanks, or 15 such as have been already ground on one face to such spherical curvature. In either case the shape and size of the facet is made to correspond with the lens intended to be seated thereon; and its face is accurately 20 centered and squared to the radial line of the spherical curvature of the opposing surfaces of the mold portions 20, 21, and accurately spaced from said surfaces. It will be readily understood that practically absolute accuracy may be readily secured by such 25 construction, so when a series of like segments are produced in the mold and assembled in the mold shell 10 as indicated in Fig. 3, each facet will be accurately located 30 relative to the focal axis of grinding. In arranging the mold preliminary to forming these segments, the facet-forming portion 26 may be accurately adjusted in its opening so as to properly set the axial line 30 of the 35 facet, as indicated in Fig. 7, the operation otherwise being obvious from the drawing. It will be readily understood also that when two or more series of segments are employed, arranged in different zones as indicated in 40 Figs. 3 and 4, the wall portion 22 of the segment mold will be correspondingly varied for each series of segments without varying the determined uniform relation of the facets to the focal axes when the segments 45 are properly assembled in the lens-holder molding shell 10 as indicated; and that the pitch-surfacing 3 of the lens-holder 2, as formed therein, will provide similarly accurate lens-attaching facets.

50 The lens blanks which are attached to a holder having flat facets as shown to the right of Fig. 1, may vary from the normal indicated at w , so as to require excessive or unequal grinding,—as for instance the prismatic form of blank indicated at y . This 55 excessive grinding is done on the first mounting, thus reducing all the blanks to like thickness with one face convexly ground to the required curvature;—as indicated at 60 z to the left of Fig. 1, where the lenses are shown mounted upon the corresponding concaved facets so as to properly expose the other face to the second grinding process which results in the finished lens indicated 65 at w . Heretofore the rough-edged blanks

have been mounted upon the lens-holders, and both faces ground before beveling the edges; but I am enabled to double-bevel the edges first, making this beveling true to one face of the lens regardless of the other as 70 indicated at y , thus providing blanks of uniform shape and size so far as the flat mounting face y^1 and the beveled edge is concerned, which greatly facilitates the accurate setting of the blanks upon the correspondingly formed facets; any excess grinding required upon the exposed face, as on lens y , merely equalizing the edge beveling, and the final face grinding producing a finished product which is not liable to be 80 scratched or otherwise damaged as when the beveling of the edges is effected by a subsequent operation.

To further facilitate the proper placing of the lenses upon the facets, I preferably 85 provide setting means consisting as indicated in Fig. 5 of an oval guide ridge 35 parallel with the rim of the facet. This ridge forms a groove in the raised lens holder facet which the operator can readily 90 see in setting the lens and which enables him to accurately and quickly place the latter. The ridge 35 is readily formed on the segment by means of a corresponding groove 95 35^a provided in the segment mold (Fig. 7). 95

As indicated in Figs. 10, 11, and 12 my segmental lining may also be advantageously applied to forming other than spherical lens holders, though the need thereof in the latter case is considered to be 100 practically greater. As shown in these figures the base portion 10^a of the mold is cylindrically curved, and segments of corresponding form, as made in a correspondingly modified segment mold such as shown 105 in Fig. 8, are fixed either to the cylindrically convexed or concaved surfaces as required; or such surface may obviously be made plane, with correspondingly formed lining segments if flat lenses are to be produced, 110 or adapted for prismatic lenses if desired. After my improved segmental mold has been thus built up in any required form, solid duplicates thereof may be cast therefrom of suitable material and be similarly 115 used in molding like lens holders.

What I claim is:—

1. A lens-block mold comprising a spherically-surfaced base portion, and a sectional facing for said spherical surface made up 12 of separately formed facet-forming spherical segments the marginal portions of each of which abut adjacent segments.

2. A lens-block mold comprising a spherically-surfaced base portion, and a sectional facing for said spherical surface made up of 12 separately formed facet-forming spherical segments arranged in a spherical zone, the side walls of each segment abutting adjacent segments.

3. A lens-block mold comprising a spherically-surfaced base portion, and a sectional facing for said spherical surface made up of separately formed facet-forming spherical segments arranged in zone series, the segments of each series being different in contour from those of each other series substantially as set forth.
4. A facet-forming spherical-segment mold comprising base and coping portions providing parallel spherically-curved surfaces and one of which is provided with a facet-forming portion squared to a radial line of said surfaces, and segment walls between said surfaces inclosing said facet-forming portion.
5. A facet-forming spherical-segment mold comprising base and coping portions providing parallel spherically-curved surfaces, a facet-forming fitting to one of said portions squared to a radial line of said surfaces, and segment walls between said surfaces inclosing said facet-forming portion.
6. A facet-forming spherical-segment mold comprising base and coping portions providing parallel spherically-curved surfaces, an adjustable facet-forming fitting to one of said portions squared to a radial line of said surfaces, and segment walls between said surfaces inclosing said facet-forming portion.
7. A facet-forming spherical-segment mold comprising base and coping portions providing parallel spherically-curved surfaces, and one of which is provided with a facet-forming portion squared to a radial line of said surfaces, and a segment-wall portion fitted between said spherically curved surfaces.
8. A facet-forming spherical-segment mold comprising base and coping portions providing parallel spherically-curved surfaces, one of which is provided with a facet-forming portion squared to a radial line of said surfaces, and a segment-wall portion fitted between said spherically curved surfaces; said segment-wall portion having opposite parallel walls and converging intersecting walls substantially as set forth.
9. A lens-block mold having lens facets which are ridged to form lens-setting grooves.
10. A facet-forming segment mold comprising base and coping portions providing opposing surfaces, and segment-walls between said surfaces; one of said portions being provided with a lens facet which is formed with a lens-setting groove.
11. A facet-forming segment mold comprising base and coping portions providing opposing surfaces, and segment-walls between said surfaces; one of said portions being provided with a lens facet.
12. A lens-block mold comprising a spherically-surfaced base portion, and a sectional facing for said spherical surface made up of separately formed facet-forming spherical segments arranged in zone series, the segments of each series being different in contour from those of each other series, and the marginal portions of each segment abutting adjacent segments.

In testimony whereof I affix my signature in presence of two witnesses.

WILLIAM W. ESSICK.
